US0D1024032S

(12) **United States Design Patent** (10) **Patent No.:** **US D1,024,032 S**
(45) **Date of Patent:** **** Apr. 23, 2024**

(54) **SLEEP-INDUCING EARBUD**

(71) Applicant: **LG ELECTRONICS INC.**, Seoul (KR)

(72) Inventors: **Jasoo Cho**, Seoul (KR); **Seungpyo Noh**, Seoul (KR); **Yangtae Kwon**, Seoul (KR); **Jeongkeun Choi**, Seoul (KR)

(73) Assignee: **LG ELECTRONICS INC.**, Seoul (KR)

(**) Term: **15 Years**

(21) Appl. No.: **35/516,477**

(22) Filed: **Feb. 3, 2023**

(80) **Hague Agreement Data**

Int. Filing Date: **Feb. 3, 2023**

Int. Reg. No.: **DM/226900**

Int. Reg. Date: **Feb. 3, 2023**

Int. Reg. Pub. Date: **Mar. 3, 2023**

(30) **Foreign Application Priority Data**

Sep. 26, 2022 (KR) 30-2022-0039264

(51) **LOC (14) Cl.** **14-01**

(52) **U.S. Cl.**

USPC **D14/223**

(57) **CLAIM**

The ornamental design for a sleep-inducing earbud, as shown and described.

DESCRIPTION

1. Sleep-inducing earbud

1.1 : Front perspective view

1.2 : Back perspective view

1.3 : Front

1.4 : Back

1.5 : Left

1.6 : Right

1.7 : Top

1.8 : Bottom

1.9 Front perspective view

The broken lines shown in reproductions 1.1 to 1.8 depict portions of the sleep-inducing earbud and the broken lines in 1.9 depict environment; all broken lines form no part of the claimed design.

1 Claim, 9 Drawing Sheets
